UNITED STATES PATENT OFFICE.

WILLIAM R. BLOWERS, OF TORONTO, ONTARIO, CANADA.

DESIGN FOR A TIRE-TREAD.

43,335.

Specification for Design.

Patented Dec. 10, 1912.

Application filed October 7, 1912. Serial No. 724,483. Term of patent 7 years.

To all whom it may concern:

Be it known that I, WILLIAM R. BLOWERS, a citizen of the United States of America, and resident of the city of Toronto, in the county of York, Province of Ontario, in the Dominion of Canada, have invented a new, original, and ornamental Design for a Tire-Tread, of which the following is a specification, reference being had to the accompanying drawings, forming part thereof.

In the drawings, Figure 1 is a perspective view of a portion of a tire tread constructed in accordance with my invention. Fig. 2 is an enlarged plan view of a portion of my tire tread.

The design consists in the arrangement of a pair of circumferentially arranged ribs placed one to each side of the center of the tire tread. These ribs are joined at regular intervals by diagonally arranged transverse

ribs and a plurality of diagonally arranged transverse ribs extend laterally from the outer sides of said circumferential ribs, said outer ribs being in substantially parallel relation the one to the other and arranged preferably opposite and extending from the adjacent ends of the central transverse ribs and also extending in acute angular relation thereto, the outer ribs with the center ribs forming a double arrangement of reverse V-shaped ribs.

What I claim is:

The ornamental design for a tire tread as shown and described.

Signed at the city of Toronto, Ontario, Canada, this 25th day of Sept., 1912.

WILLIAM R. BLOWERS.
